Inventor:

Joseph Hoffacker

UNITED STATES PATENT OFFICE.

JOSEPH HOFFACKER, OF NEW YORK, N. Y.

LOCK AND KEY.

Specification of Letters Patent No. 21,962, dated November 2, 1858.

To all whom it may concern:

Be it known that I, JOSEPH HOFFACKER, of the city, county, and State of New York, have invented a new and useful Improvement in Locks and Keys; and I do hereby declare that the following is a full, clear, and exact description thereof, reference being had to the annexed drawings, making part of this specification, in which—

10 Figure 1 is a horizontal view of the door, in which the lock and the bolt hole are inserted; Fig. 2, a vertical section of the lock; Fig. 3, a front view of the bolt head; Fig. 4, an elevation of the bolt hole; Fig. 5, a 15 section of the bolt hole; Fig. 6, a horizontal section of the lock; Fig. 7, an elevation of the key.

The same letters of reference denote corresponding parts in these various figures.

20 The nature of my invention consists in constructing a lock, which is closed or locked by the bolt shooting forward and upward simultaneously, and which is opened or unlocked by a screw key urging the bolt downward and backward.

To enable others skilled in the art to make and use my invention I will proceed to describe its construction and operation.

The lock consists of the bolt *a*, the barrel 30 *c*, in which the bolt is made to move, the three springs *o*, *n* and *i* which urge the bolt forward and upward, and the lever *d* by which the lock may be closed on the inside. The bolt *a* is provided with a head *b* which 35 is so formed as to correspond with the bit of the screw *r*, *s* serving as a key for this lock. The shape of the bolt head is fully shown on the drawings, but the same may be varied at pleasure; care being only taken, 40 that the parts of the same, which are to be touched by the bit, are to be shaped in such a manner, that a certain bit will act as a screw and wedge on the same, thereby lowering the bolt head and urging it back; and 45 that no other bit shall act in the same manner.

The back part of the bolt is surrounded by a spiral spring *o* which urges the bolt forward. The bolt has three notches at 50 *e*, *e* in which the side spring *i* fits; the said side spring serves to hold the bolt when the same is thrown back and for this purpose the said spring is brought in connection with the lever *d* so as to facilitate the closing of 55 the lock from the inside. The third spring *n* acts upon the bolt vertically, the bolt being

made slanting, this spring will elevate the bolt when the same is thrown forward. The lever *d* when drawn backward will cause the spring *i* to release its hold upon the projection at *e* from the notch of the bolt, thereby allowing the bolt to be urged forward by the spiral spring.

The bolt hole *m* in the door is so formed as to be lower on the outside than on the inside, in such a manner that the head of the bolt may catch the projection *u* of the bolt hole when moved upward. This bolt hole is pierced by two key holes *f* and *g*. One key hole serves for the outside and the other 60 for the inside of the door, the one leading to the lower, the other to the upper part of the bolt head. These key-holes are made in the form of female screws and the key *r* *s* is screwed into the same when the lock is to 75 be opened.

The key consists of the knob or handle *q*, the stem *v* and the bit *t*. The stem forms a cylinder, on which the main screw *r* is cut, and another smaller cylinder *s* on which 80 screwthreads are partially cut.

The key is screwed into the key hole by the large screw *r*. During the progress made the smaller screw threads will slightly elevate the bolt head until the bit has worked 85 itself into the incision of the bolt head; on continuing the screwing operation the bolt-head is pressed down, its hold upon the projection of the bolt hole is released, the side spring is forced out of the notch *c*, the bolt 90 is thrown back to *d'* and the side spring lodges in the notch *e'*, thereby keeping the bolt in its place.

The door handles *h* and *k* turn on an axle but have no direct connection with the bolt. 95 These two door handles have such a position, that when the outer handle *k* is turned, the inner handle *h* comes in contact with the lever *d*, throws it back and thereby causes the lock to be shut or locked. After the bolt 100 is drawn back, the door does not open until a gentle pressure is applied to the same.

The peculiar features distinguishing my lock and key from all others in use are: 1. The combination of the bolt with the barrel and the three springs. 2. The construction of the bolt and especially of the bolt head. 3. The combination of the door-handles with the lever by which the door may be locked without the application of the key. 4. The construction of the bolt hole, so as 110 to permit the bolt of catching into the same

horizontally and vertically. 5. The two key holes, one for the use on the outside, the other for the inside. 6. The construction and operation of the screw key.

7. It is evident that this lock has many advantages over those at present in use especially in the difficulty of opening or picking the same by a skeleton key. I deem it proper to add that I have represented this lock to be attached to a door, but it may be applied with equal effect to chests, safes, drawers or boxes.

8. What I claim as new and desire to secure by Letters Patent is:

9. 1. Constructing a lock which is closed or locked by the bolt shooting forward and up-

ward and which is opened or unlocked by a screw key urging the bolt downward and backward substantially as described.

10. 2. The construction of the bolt in combination with the barrel and the three springs substantially as described.

11. 3. The combination of the door handles with the lever substantially as described.

12. 4. The construction and operation of the screw key substantially as described.

13. New York August 24, 1858.

JOSEPH HOFFACKER.
